DESIGN FOR AN INKSTAND.

SPECIFICATION forming part of Design No. 14,425, dated November 20, 1883.

Application filed October 24, 1883. Term of patent 3½ years

To all whom it may concern:

Be it known that we, ADRIAN COOKE, CHARLES W. SCHRIEBER, and JOSEPH S. MORGAN, citizens of the United States, residing at Dubuque, in the county of Dubuque and State of Iowa, have invented and produced a new and original Design for an Inkstand, of which the following is a description, reference being had to the accompanying drawing, forming part thereof.

A represents a horseshoe-shaped base, on which is supported another horseshoe-shaped frame, B, provided with pins C. A pincushion, D, is attached to the frame in front.

E represents the ink-bottle in a suitable ring, F.

We claim—

The design for a fancy inkstand, consisting of the horseshoe-shaped base A, the arched frame B, in combination with the centrally-placed ink-holder E and the pincushion D, as shown and described.
